UNITED STATES PATENT OFFICE.

JOHN G. LEWIS, OF ST. LOUIS, MISSOURI.

SEWING-MACHINE.

1,156,607.

Specification of Letters Patent.

Patented Oct. 12, 1915.

Application filed March 12, 1906. Serial No. 305,479.

To all whom it may concern:

Be it known that I, JOHN G. LEWIS, a citizen of the United States, residing in the city of St. Louis, in the State of Missouri, have invented a certain new and useful Sewing-Machine, of which the following is such a full, clear, and exact description as will enable any one skilled in the art to which it appertains to make and use the same, reference being had to the accompanying drawings, forming part of this specification.

My invention relates to sewing machines, and more particularly to blind stitch sewing machines, though some of the features of my invention are applicable to other types of sewing machines.

The general construction and operation of my machine is similar to that shown and described in Patent 862,830, issued to me August 6, 1907, and many of the features shown in the present application are not claimed in this application because the same are described and claimed in my said prior patent.

One of the principal objects of my invention is to provide improved means for insuring the proper coöperation of the needle and the beak of the looper in the different lateral positions of the needle and in uniform relation to the time of the take-up;

Another object of my invention is to provide improved means for operating and adjusting the back guides.

Still another object of my invention is to provide an improved form of needle guide.

In the accompanying drawings which illustrate a machine made in accordance with my invention, Figure 1 is an end elevation of a portion of the machine, the arm being shown in section; Fig. 2 is a detail view of a portion of the guide-operating mechanism; Fig. 3 is a front view of some of the parts shown in Fig. 2; Fig. 4 is a top plan view of a portion of the machine, the hook and its housing being removed; Fig. 5 is a longitudinal section through the parts for operating the hook; Fig. 6 is a top plan view of a part of the arm; Fig. 7 is partly a front elevation and partly in section; Fig. 8 is a section showing the looper mechanism; and Figs. 9 and 10 are diagrammatic views illustrating the coöperation of the hook and needle.

Like marks of reference refer to similar parts in the several views of the drawings.

15 is the main housing of the machine which carries an arm 16 extending parallel therewith.

17 is the main shaft passing through the housing 15. The shaft 17 is provided with cams 18 from which motion is communicated to shafts 19 and 20 passing through the arm 16 and operating the back guides and feed dog as will be hereinafter more fully described. The said shaft is also provided with an eccentric 21 operating a pivoted bar 22 for reciprocating the needle. Said shaft is also provided with the usual switch cam 23 operating through adjusting-segment-and-bar connections 24 for laterally vibrating the needle. The shaft 17 is also provided with a cam 12 actuating the take-up 13 which is pivoted at 14. The connections 24 are pivoted to the upper end of an L-shaped arm 25, which is secured to a rock shaft 26 carrying the needle bar 27. The needle bar 27 is connected with the lever 22 by means of a link 28. This link, instead of projecting toward the hook mechanism as in my previous application, is made to project in the opposite direction, as clearly shown in Figs. 7, 9 and 10, and the said link is made the same length, or substantially the same length, as the radius of the hook for purposes which will be more fully pointed out hereinafter. The needle bar 27 is provided with a needle 29, and secured to the casing 15 is a needle guide 30 coöperating with the said needle 29. This needle guide 30, as most clearly shown in Fig. 4, has its face 90 curved in the direction of vibration of the needle, the curve being a segment of a circle having as its center the pivotal point of the shaft 26, so that the lateral vibration of the needle in a circular arc does not vary the distance between the needle and guide.

31 is the rotary hook provided with the usual beak 32.

The hook 31 is contained in a housing 33 which is provided with a hub 34 projecting into an opening in the end of the main housing 15. This housing 33 also contains the gearing for driving the hook 31. The said hook 31 is secured on the end of a shaft 35, the opposite end of which is provided with a small spiral gear 36. This gear 36

meshes with a larger gear 37. The gears 36 and 37 are so proportioned as to cause the hook 31 to rotate twice to each rotation of the main shaft 17 upon which the gear 37 is mounted. The gear 37 is secured to the main shaft by means of a key 38 so that the said gear may slide longitudinally of the main shaft but be incapable of independent rotation. The said gear 37 is provided with 10 a sleeve 39 surrounding the shaft 17 and extending within the sleeve 34 on the gear casing 33. The sleeve 39 is provided with a peripheral, annular groove 40, which is engaged by a shifting block 41. This block 15 41 is pivotally carried in an opening 42 eccentrically located in the upper end of a rock shaft 43. The rock shaft 43 passes through a bearing 44 secured in the main casing 15 and is provided with a collar 45 20 which prevents its further passage through the said bearing 44. It will be evident that when the rock shaft 43 is oscillated the shifting block 41 will be moved back and forth by means of the eccentric and thus 25 shift the spiral gear 37 longitudinally on the shaft 17. This will cause the said gear 37 in addition to its rotating function to act as a rack to operate the gear 36, which will thus act as a pinion, and, consequently, 30 the beak 32 of the hook 31 will be retracted or advanced in its path of rotation for purposes hereinafter to be described. In order to operate the shaft 43 the same has rigidly secured to it an arm 46 connected by a link 35 47 with the L-shaped arm 25 by which the needle bar is vibrated laterally. The rotary hook 31 carries the usual bobbin case 48 and bobbin 49.

The arm 16 has slidingly mounted upon 40 its end a back guide formed of two parts 50 and 51. Each of the parts 50 and 51 is provided with a downward projection 52 and 53 respectively. The projection 53 on the part 51 has pivotally secured to it a feed dog 54, which dog is thus operated in one direction by the movement of the guide 51, and in the other is operated by an arm 55 actuated through the shaft 19. To each of the projections 52 and 53 is pivoted one end 45 of a link 56, the opposite end of which is pivoted to an arm 57 loosely mounted on the shaft 20, the link 56 and arm 57 forming a toggle joint for operating the guide 50 or 51. Each of the arms 57 is provided with 50 a curved arm 58 passing through a notch in an arm 59 rigidly secured on the shaft 20. A spring 60 surrounds each of the curved arms 58 so that the forward motion of the arm 59 is not connected directly to the toggle mechanism but only through the said spring 60, thus making a yielding connection between the toggle mechanism and the operating arm. Each of the curved arms 58 is provided with a pin 68 which is engaged by the arm 59 so that the rearward 55

movement of said arm is positively communicated to the toggle mechanism. In order to provide each of the parts of the guide with an adjustable positive stop, I place in each of said guides a screw 61 provided with a lock nut 62. These screws 61 may abut against any suitable part of the machine forming a solid stop. I prefer, however, in order to provide additional means for adjusting the movement of the guides to have the said stop screws strike against a sliding stop plate 63. This stop plate 63 is provided with two sets of stop faces 64, each set consisting of three or more faces arranged in different planes, and the said plate 63 is held in position by means of a spring 65 engaging with notches 66 on the lower edge of said plate. The guides may thus be quickly given a predetermined difference of adjustment for different thicknesses of goods by simply moving the plate longitudinally so as to cause the guide screws 61 to strike against the different faces 64.

The link 28, as hereinbefore described, projects on the opposite side of the arm 22 from the rotary hook mechanism and the length of the said link is approximately equal to the radius of the hook. It will be evident from Figs. 9 and 10 that by this 90 construction the eye of the needle will always bear the same relation to the periphery of the hook at a given point in the revolution of the main shaft no matter what the lateral position of the needle may be, as the 100 needle is raised or lowered by the lateral vibration in a path corresponding to the periphery of the hook. Thus, if the eye of the needle is adjusted to properly co-operate with the beak 32 when in the central position, as shown in full lines in Figs 9 and 10, and the needle is vibrated laterally to the right, as shown in Fig. 9, the eye will be raised along a line corresponding with the periphery of the hook and thus when the bar 110 22 is in a given position corresponding to a certain point in the revolution of the main shaft, the eye of the needle will remain in the same position relative to the periphery of the hook no matter what the lateral position of the needle may be. It will be evident, however, that some means is necessary for retracting or advancing the beak 32 of the hook in order to make it properly co-operate with the eye of the needle, for it is 115 evident that if such compensation of the looper is not made the beak will always be in the central position, as shown in full lines in Figs. 9 and 10, when the eye of the needle is in proper relation to the periphery 120 of the hook. While in the position shown in dotted lines in Fig. 9 the beak of the hook will have traveled past the needle before the proper relation is established between the eye of the needle and the periphery of 125 130

the hook, and in the position shown in dotted lines in Fig. 10, the beak will not have traveled a sufficient distance. The proper advancing or retracting of the hook 31 is obtained by the shifting of the gear 37 longitudinally of the shaft 17; as has been hereinbefore described. When the needle is moved to the right as shown in dotted lines in Fig. 9, the movement of the L-shaped arm 25 will be to the left and this will be communicated through the link 47 and arm 46 to the shaft 43 and this will cause the shifting block 41 to move to the right and thus carry the spiral gear 37 along the shaft 17 to the right. The spiral gear 37 will thus act upon the gear 36 as a rack upon a pinion and partially rotate the said gear in the direction of the dotted arrow in Fig. 5, or at least tend to rotate it in this direction. As the gear itself is traveling in the opposite direction in the operation of the machine, this will simply retard the beak of the hook and this retarding of the beak of the hook will cause it to lag behind so that in place of reaching the position shown in full lines in Fig. 9, it will only reach the position shown in dotted lines and thus will be in the proper coöperative relation to the eye of the needle. In case the needle is shifted to the left the operation will be the reverse and the beak of the hook will be advanced so as to cause it to reach the position shown in dotted lines in Fig. 10, and the hook will still be in proper coöperative relation with the eye of the needle at the given point in the revolution of the main shaft. Inasmuch as the beak of the looper and the eye of the needle coöperate at the same point or degree in the revolution of the main shaft in all the lateral positions of the needle it will be evident that the take-up will be in harmonious action with the needle and the looper in all the lateral positions of the needle. Another advantage of my construction is that inasmuch as the passage of the eye of the needle beyond the path of the beak of the looper is the same in all the lateral positions of the needle, and the distance between the eye of the needle and the path of the beak at the time of coöperation is also the same in all said positions, the withdrawal of the needle at the time of coöperation is the same for all the lateral positions, and, consequently, the same width of loop is always formed. The operation of the switch cam 23, restoring the needle bar to its primary path of reciprocation when the needle is out of engagement with the work, also acts through the connections described to slide the worm-sleeve 37 back to its primary position, thereby restoring the hook to its initial time-relation to the shaft, so that the cast off from the hook occurs in proper time relation to the drawing action of the take-up.

The operation of the back guides 50 and 51 is evident from the description previously given, said guides being reciprocated by the motion of the rock shaft 20 communicated through the arm 59 and springs 60 to the toggle mechanism. The advantage of this construction is that it is not necessary to compress the springs 60 until about the time of coöperation between the needle and the guide, *i. e.*, when the screws 61 come in contact with plate 63, as the said springs simply communicate the movement of the toggle mechanism and acts as a rigid connection until sufficient resistance is offered to the movement of the guides to cause a compression of the spring 60 and owing to the increased pressure gained by the toggle joint a light spring can be used, as a much greater force will be imparted to the back guide than that required to compress the spring 60. The guides may be properly set in the first instance by means of the screws 61 and lock nut 62, after which it is easy to adapt the machine for goods of different thicknesses by simply moving the stop plate 63 longitudinally so as to cause the different faces 64 to coöperate with the stops 61.

Having fully described my invention, what I claim as new and desire to secure by Letters Patent of the United States, is:

1. In a sewing machine, stitch forming mechanism comprising, in combination, a looper having its plane of movement parallel to the needle, a reciprocating needle, adjustable means to vibrate said needle laterally and with respect to said looper between selected paths of reciprocation in a field of vibration, which said paths of reciprocation intersect different points in the looper-beak path, and means for forming substantially the same width of loop to receive the looper in all the lateral positions to which the needle may be vibrated.

2. In a sewing machine, stitch forming mechanism comprising, in combination, a looper having its plane of rotation parallel to the needle and rotating unidirectionally, a reciprocating needle, adjustable means to vibrate said needle laterally and with respect to said looper between any selected paths of reciprocation within a field of vibration, which said paths of reciprocation intersect different points in the circular path of the looper-beak, and means for forming substantially the same width of looper-beak-receiving loop in all of the lateral positions to which the needle may be vibrated.

3. In a sewing machine, stitch forming mechanism comprising, in combination, a looper, a needle vibrating between different paths of reciprocation which intersect the looper-beak path at different points in said looper-beak path and also at different points in the length of the needle-paths, of means for effecting coöperation of the looper-beak.

with the needle at substantially uniform time in the cycle of machine-operation, in any of the lateral positions of the needle.

4. In a sewing machine, the combination of a looper, a needle vibrating laterally between paths which intersect different points in the looper-beak path, means for varying the thrust of the needle to effect its uniform passage past the looper-beak path in the different lateral positions of the needle, and compensating mechanism acting in harmony with the vibration of the needle and effecting coöperation of the looper-beak with the needle at substantially uniform time in the cycle of machine-operation.

5. In a sewing machine, the combination with a laterally vibrating needle-holder, and a looper, of a rotating gearing for actuating the looper, and operating connections between the needle-holder and gearing for accelerating or retarding the looper-actuating gear-member as the needle-holder moves in vibration.

6. In a sewing machine, the combination with a rotary looper, of a laterally vibrating needle-holder, rotating gears driving said looper, and means controlled by movement of the needle-holder to vary the relation between the rotating gear elements to accelerate or retard the looper.

7. In a sewing machine, stitch forming mechanism comprising, in combination, a looper rotating unidirectionally, a needle, adjustable means to vibrate said needle laterally between different selected paths of reciprocation crossing the circular path of looper-beak movement at different points, means for varying the thrust of the needle to cause its uniform passage past the arc of the looper-beak path in all the lateral positions to which the needle may be vibrated, and means for effecting coöperation of the looper beak with the needle in substantially uniform time in the cycle of machine-operation.

8. In a sewing machine, the combination with stitch-forming mechanism comprising a laterally vibrating needle and a looper, of a pair of spiral gears driving said looper, and means for shifting one of said gears longitudinally to retard or advance said looper.

9. In a sewing machine, the combination with stitch forming mechanism comprising a laterally vibrating needle and a looper, of a pair of spiral gears driving said looper, and means controlled by the lateral vibration of the needle for shifting one of said gears longitudinally to compensate said looper.

10. In a sewing machine, the combination with stitch forming mechanism comprising a reciprocating and laterally vibrating needle and a looper rotating in a plane substantially parallel with the paths of vibra-

tion of the needle and on a fixed axis substantially at right angles to the plane of reciprocation of said needle, of means for varying the depth of thrust of said needle in its different lateral position in proportion to the curvature of the path of travel of the looper beak.

11. In a sewing machine, the combination with stitch forming mechanism comprising a reciprocating and laterally vibrating needle and a looper rotating in a plane substantially parallel with the path of vibration of the needle on a fixed axis substantially at right angles to the plane of reciprocations of said needle, of means actuated by the lateral vibration of said needle for varying the thrust of said needle proportionally to the curvature of the path of travel of the beak of said looper.

12. In a sewing machine, the combination with stitch forming mechanism comprising a reciprocating and laterally vibrating needle and a looper rotating in a plane substantially parallel with the path of vibration of said needle and on an axis substantially at right angles to the path of reciprocation of said needle, of a movable member for actuating said needle and a link connecting said needle and member, said link being substantially of the same length as the radius of the looper and extending from the side of said member opposite to the said looper.

13. In a sewing machine, the combination with stitch forming mechanism comprising a reciprocating and laterally vibrating needle and a looper rotating in a plane substantially parallel with the path of vibration of said needle and on an axis substantially at right angles to the path of reciprocation of said needle, of an oscillating member for actuating said needle, a link connecting said needle and member, said link being substantially of the same length as the radius of the looper and extending from the side of said member opposite to said looper, and compensating means for said looper controlled by the lateral vibration of said needle.

14. In a sewing machine, the combination with stitch forming mechanism comprising a reciprocating and laterally vibrating needle and a looper rotating in a plane substantially parallel with the path of vibration of said needle and on an axis substantially at right angles to the path of reciprocation of said needle, of an oscillating member for actuating said needle, a link connecting said needle and member, said link being substantially of the same length as the radius of the looper and extending from the side of said member opposite to said looper, a pair of spiral gears driving said looper, and means controlled by the lateral vibration of said needle for shifting one of said gears longitudinally to compensate said looper.

15. In a sewing machine, the combination

- with a laterally vibrating needle carried by a pivoted member, of a needle guide co-operating with said needle before it enters the goods and having its face curved in the direction of the vibration of said needle.
16. In a sewing machine for blind stitching, the combination with stitch forming mechanism, of a reciprocating back guide, a movable member for actuating said guide, connections actuated from the driving shaft of the machine for operating said movable member, and a spring interposed between said guide and movable member.
17. In a sewing machine for blind stitching, the combination with stitch forming mechanism, of a reciprocating back-guide to bend the goods, a driving part for said back guide having a positive movement in excess of that required to actuate said back-guide, and a spring interposed between said back-guide and driving part.
18. In a sewing machine for blind stitching, the combination with stitch forming mechanism, of a reciprocating back guide, an adjustable positive stop for said guide, a movable member for actuating said guide, and a spring interposed between said guide and movable member.
19. In a sewing machine for blind stitching, the combination with stitch forming mechanism, of a two-part back guide, a movable member for actuating said guide, and a spring interposed between each part of said guide and said movable member.
20. In a sewing machine, the combination with stitch forming mechanism including a laterally vibrating needle, of a needle guide co-operating with the needle before it enters the goods, the distance between the path of the needle and the guide being the same in all the lateral positions of the needle.
21. In a sewing machine for blind stitching, a spring mounted guide for the goods, and means whereby the spring is brought into its strongest action at the time of co-operation between the guide and the needle.
22. In a sewing machine for blind stitching, an adjustable spring mounted guide for the goods, and means whereby the spring is brought into its strongest action at the time of co-operation between the guide and the needle.
23. In a sewing machine for blind stitching, a spring mounted guide for the goods, and means whereby the spring is brought into action substantially only at the time of co-operation between the guide and the needle.
24. In a sewing machine for blind stitching, an adjustable spring mounted guide for the goods, and means whereby the spring is brought into action substantially only at the time of co-operation between the guide and the needle.
25. In a sewing machine for blind stitching, the combination with stitch forming mechanism, of a reciprocating guide, a spring for said guide, and means for multiplying the pressure imparted to said guide by said spring.
26. In a sewing machine for blind stitching, the combination with stitch forming mechanism, of a reciprocating back guide, and toggle connections for actuating said guide.
27. In a sewing machine for blind stitching, the combination with stitch forming mechanism, of a reciprocating back guide, toggle connections for actuating said guide, a movable member for actuating said toggle connections, and a spring interposed between said movable member and toggle connections.
28. In a sewing machine for blind stitching, the combination with stitch forming mechanism, of a two-part back guide, toggle connections for each part of said guide, and means for simultaneously actuating both of said toggle connections.
29. In a sewing machine for blind stitching, the combination with stitch-forming mechanism, of a two-part back guide, toggle connections for each part of said guide, a movable member, and a spring interposed between each of said toggle connections and said movable member.
30. In a sewing machine, the combination with stitch-forming mechanism, of a back guide, and a movable stop plate for said back guide provided with bearing surfaces in different planes.
31. In a sewing machine, the combination with stitch-forming mechanism, of a reciprocating back guide, and a movable stop plate for said guide provided with bearing surfaces in different planes.
32. In a sewing machine, the combination with stitch-forming mechanism, of a reciprocating back guide, a movable stop plate for said guide provided with bearing surfaces in different planes, and an adjustable stop carried by said guide and co-operating with said stop plate.
33. In a sewing machine, the combination with stitch forming mechanism, of a two part back guide, and a movable stop plate for said guide provided with bearing surfaces in different planes.
34. In a sewing machine, the combination with stitch forming mechanism, of a reciprocating two part back guide, and a movable stop plate for said guide provided with bearing surfaces in different planes.
35. In a sewing machine, the combination with stitch forming mechanism, of a two part reciprocating back guide, a movable stop plate for said guide provided with bearing surfaces in different planes, and an adjustable stop carried by said guide and co-operating with said stop plate.

36. In a sewing machine, the combination with stitch forming mechanism, of a back guide, a movable stop plate for said guide provided with bearing surfaces in different planes, and retaining means for said stop plate.

37. In a sewing machine, the combination with stitch forming mechanism, of a back guide, a movable stop plate for said guide provided with bearing surfaces in different

planes, and a spring retaining device for said stop plate.

In testimony whereof, I have hereunto set my hand and affixed my seal in the presence of the two subscribing witnesses.

JOHN G. LEWIS. [L.S.]
